UNITED STATES PATENT OFFICE.

JACOB SALÉ, OF PHILADELPHIA, PENNSYLVANIA.

FOLDING BABY-CARRIAGE.

SPECIFICATION forming part of Letters Patent No. 584,898, dated June 22, 1897.

Application filed February 17, 1896. Serial No. 579,681. (No model.)

To all whom it may concern:

Be it known that I, JACOB SALÉ, a citizen of the United States, residing in the city of Philadelphia, State of Pennsylvania, have invented a new and useful Improvement in Gearing for Folding Baby-Carriages, of which the following is a specification.

In the accompanying drawings, Figure 1 is a perspective view of the running-gears when in position. Fig. 2 shows the gearing folded up.

Similar letters of reference indicate corresponding parts.

The object of my invention is to furnish a baby-carriage that may be neatly and compactly folded up, thus being more readily carried about and stored away.

The invention consists of an acting-bar pivoted to two sets of cross-pieces hinged to the side bars by bolts at their inner ends and a cross-bar loosely fitting upon the screw-threaded rear end thereof, upon which is a nut used to lock the device.

In the drawings, A represents the acting-bar, and B the cross-pieces, hinged to the side-bars C, the inner ends of each set being pivoted upon a bolt F. The acting-bar A is connected to these bolts and screw-threaded upon its rear end, the cross-bar E fitting loosely upon the acting-bar and at its ends

adapted to engage the side-bars C and hold them in their extended position, and a nut D upon the acting-bar A, adapted to engage the cross-bar E, thereby locking the device in its extended position and making the whole gear firm and steady. The handle-bar G fits loosely upon one of the side-bars, C', and is stationary upon the other, C².

In closing the carriage the locking-nut D is moved forward on the screw-threaded end of bar A, the handle-bar G is lifted upward, and drawing backward bar A the cross-pieces fold together, bar A being the lever for closing and opening the coach, and nut D the locking device.

I claim as new and desire to secure by Letters Patent, to wit:

In a folding-carriage gear, the combination of side-bars connected by jointed cross-pieces, an acting-bar pivotally connected to the cross-pieces, a cross-bar E engaging the side-bars and a nut D upon the screw-threaded end of the acting-bar, substantially as described.

Dated the 23d day of May, A. D. 1895.

JACOB SALÉ.
